OPHTHALMOSCOPE

John T. Armbruster, Niagara Falls, N.Y., assignor to
American Optical Company, Southbridge, Mass.

Filed July 22, 1960, Ser. No. 61,487

Term of patent 14 years

(Cl. D57—1)

Fig. 1

Fig. 2

Fig. 3

Fig. 4

Fig. 5

Fig. 6

Fig. 1 is a front elevational view of an ophthalmoscope showing my new design;

Fig. 2 is a side elevational view thereof;

Fig. 3 is a top plan view thereof;

Fig. 4 is a bottom plan view thereof;

Fig. 5 is a fragmentary side elevational view thereof showing the side opposite that shown in Fig. 2; and

Fig. 6 is a rear elevational view thereof on an enlarged scale.

The side of the body portion not shown is the same as the side shown in Fig. 2.

I claim:

The ornamental design for an ophthalmoscope, substantially as shown and described.
